PREPARATION OF ALIPHATIC PERACIDS
BY OXIDATION OF ALDEHYDESJoseph E. Bludworth, Cumberland, Md., assignor
to Celanese Corporation of America, a corpora-
tion of Delaware

Application February 21, 1940, Serial No. 320,083

6 Claims. (Cl. 260—502)

This invention relates to the oxidation of aliphatic aldehydes to the corresponding per acids and relates more particularly to their oxidation by means of air or other oxygen containing gas.

An object of this invention is the oxidation of aliphatic aldehydes to the corresponding per acids in the vapor phase. Another object of this invention is the production of the per acids in high yields and their separation from the reaction products.

It has now been found that aliphatic aldehydes and particularly acetaldehyde may be directly oxidized to the corresponding aliphatic per acids. The oxidation goes very smoothly when carried out in the vapor phase and in the presence of oxygen.

According to this novel process the aliphatic aldehyde and air are mixed in predetermined quantities and then introduced into a preheater which serves to preheat the reactants before their entrance into a reaction chamber. The temperature of the reactants is raised in the reaction chamber and during passage through the chamber at a predetermined linear velocity the oxidation of the aldehyde to per acid takes place. The reaction mixture is then passed to a fractionating column together with a predetermined quantity of benzene and is separated from the per acid by azeotropic distillation. The uncondensed gases, the unreacted aldehyde and the by-products are taken off at the top of the column as an azeotrope with benzene and the per acid is removed at the base. The unreacted aldehyde is absorbed in water, distilled and recycled to the process. The benzene is separated from the acetic acid by washing with water and decantation and recycled to the fractionating column, while the remaining unreacted gases are discarded and the acetic acid recovered from the water.

In the case of acetaldehyde the oxidation reaction is illustrated by the following formula:

In order to obtain the best results it has been found that certain conditions must be adhered to and these various conditions are set out hereinafter.

The reaction in which aliphatic aldehydes may be oxidized to aliphatic per acids can be made to proceed smoothly and controllably when the oxidation is carried out in the presence of air. While air is preferably used as the oxidant, free oxygen or any gaseous mixture containing free

oxygen may also be used, so long as the only reacting component of the gaseous mixture is the oxygen contained therein. All other components should be inert. The amount of air which enters the system must be carefully controlled so that the amount of oxygen present is only sufficient to oxidize the aldehyde to the per acid and not carry the oxidation to a point where undesirable side reactions take place. To accomplish this result the air is carefully metered and only approximately 30% of the theoretical amount of oxygen necessary to oxidize the aldehyde in the reaction zone is forced into the preheater and thence into the reaction zone by the blowers.

15 The reacting gases may first be brought up to a temperature of approximately 200° F. or more in the preheater. When the gases are thus partly heated in the preheater, the reaction may be better controlled when the temperature of the gases is finally brought up to reaction temperature in the reaction chamber. Preheating avoids the dangers of any local overheating and any excessive oxidation which might occur if the temperature of the gases were brought up to the 20 reaction temperature directly in the reaction chamber and without any preheating. The heating 25 may be carried out by means of steam or by any other suitable means.

The linear velocity of the reacting gases 30 through the preheater and the reaction chamber proper may be varied from about 30 to about 300 ft./sec. with the velocity preferably about 60 ft./sec. The greater the cross-sectional area of the tubing through which the gases pass the 35 greater must be the volume velocity in order to maintain the desired linear velocity. Increased linear velocity insures the rapid removal of the desired product from the reaction zone before any secondary reactions set in, produces a high 40 degree of turbulence which eliminates localized heating, increases heat transfer by decreasing film thickness and constantly redistributes the reactants to such a degree that the reaction follows a course which can be predetermined and 45 controlled.

The time during which the reactants remain 50 in the reaction zone and are subjected to the heat of reaction is short and may vary from about 0.1 second to about 1 second, preferably about 0.2 second.

The temperature at which the reaction takes place may vary from about 350° F. to about 450° F. and preferably from about 375° F. to about 400° F. In order to attain these reaction temperatures, the reactants may be preheated to tem-

peratures of about 200° F. or more. The pressure in the preheater and reactor may be as high as 50 pounds per square inch. While such higher pressures are operative it is preferable to operate at substantially atmospheric pressure to minimize any polymerization of the aldehyde.

The use of oxidation catalysts has usually not been found to materially increase the yields of per acids. While the use of such catalysts is not excluded it is preferably to operate with the reaction zone devoid of catalyst material.

In order further to illustrate the invention, but without being limited thereto, the following specific example is given, reference being had to the accompanying drawing, all the parts being by weight.

Example

10 parts per minute of acetaldehyde from raw feed supply pipe 1 are mixed with 24.6 parts by weight per minute of recovered acetaldehyde from 2, and introduced through pump 3 and meter 4 into the inlet of preheater 5. About 22 parts per minute of air are introduced by blower 6 through meter 7, mixed with 170 parts per minute of hot recycle gases from blower 8 and meter 9 taken from the outlet of reaction chamber 10, and introduced into preheater 5 along with the 34.6 parts per minute acetaldehyde above referred to.

In preheater 5 the mixture of gases is raised to 200° F. whence they flow to reaction chamber 10 where they reach a final temperature of approximately 385° F. After leaving the reaction chamber, 142 parts per minute of benzene are introduced into the reaction gases by way of recycle line 11. This mixture of reaction products and benzene are passed into fractionation column 12 which operates under a vacuum with the pressure being about 3 pounds per square inch absolute. The uncondensable gases together with the unreacted acetaldehyde and the constant boiling mixture formed by the benzene and acetic acid, pass over from the top of the column. 6.65 parts per minute of peracetic acid are withdrawn from the reboiler 13.

In accumulator 14 the uncondensable gases (nitrogen, etc.) and the uncondensed portion of acetaldehyde are separated from the condensed products and withdrawn by means of vacuum pump 15 and fed to water absorber 16 where the vapors are scrubbed by approximately 250 parts per minute of water, the latter absorbing the acetaldehyde. The water and acetaldehyde are removed from absorber 16 by pump 17 and fed to distilling column 18 whence the acetaldehyde, after being stripped from the water, is recycled to feed pump 3 through line 2. The acetaldehyde-free water is removed from reboiler 19 and discharged to waste. The condensed products in accumulator 14, consisting of benzene, acetic acid and some acetaldehyde are withdrawn by pump 20 and fed to fractionation column 21 where the acetaldehyde is separated and then recycled to pump 3. The benzene and acetic acid are discharged from reboiler 22, through line 23, into which 20.1 parts of water per minute are added, and thence to decanter 24. The water scrubs the benzene free of acetic acid, and the dilute acid solution composed of 8.45 parts of acetic acid and 20.1 parts per minute of water is withdrawn from bottom of decanter and may be sent to any conventional acetic acid recovery unit. The acid free benzene is removed from top of decanter and recycled through line 11 to the feed inlet of fractionation column 12.

While the above reaction has been described more particularly with reference to the preparation of peracetic acid from acetaldehyde, other aldehydes such as propionaldehyde, butyraldehyde, valeric aldehyde, caproic aldehyde and other higher aldehydes may be converted into their respective per acids by this process.

It is to be understood that the foregoing detailed description and drawing is given merely by way of illustration and that many variations may be made therein without departing from the spirit of my invention.

Having described my invention, what I desire to secure by Letters Patent is:

1. Process for the production of aliphatic per-acids from the corresponding aliphatic aldehyde, which comprises oxidizing said aldehyde by pre-heating the vapor of said aldehyde to about 200° F. in admixture with an amount of oxygen theoretically insufficient to oxidize more than about 30% of said aldehyde to the per-acid, and passing the preheated mixture at a linear velocity of at least 30 feet per second through a reaction zone at a temperature of 350 to 450° F., the time of contact being from 0.1 to about 1 second and the pressure being substantially equal to atmospheric pressure.

2. Process for the production of per-acetic acid from the corresponding aldehyde which comprises oxidizing said aldehyde by preheating the vapor of the aldehyde to about 200° F. in admixture with an amount of oxygen theoretically insufficient to oxidize more than about 30% of the aldehyde to per-acid, and passing the preheated mixture at about 60 ft. per second through a reaction zone at a temperature of 350 to 450° F., the time of contact being about 0.2 second and the pressure being substantially equal to atmospheric pressure.

3. Process for the production of per-acetic acid from the corresponding aldehyde which comprises oxidizing said aldehyde by preheating the vapor of the aldehyde to about 200° F. in admixture with an amount of oxygen theoretically insufficient to oxidize more than about 30% of the aldehyde to per-acid, and passing the preheated mixture at about 60 ft. per second through a reaction zone at a temperature of 350 to 450° F., the time of contact being about 0.2 second and the pressure being substantially equal to atmospheric pressure, the greater part of the gaseous mixture emerging from the reaction zone being recycled to said zone and the remainder being treated for recovery of the per-acid.

4. Process for the production of per-acetic acid from the corresponding aldehyde which comprises oxidizing said aldehyde by preheating the vapor of the aldehyde to about 200° F. in admixture with an amount of oxygen theoretically insufficient to oxidize more than about 30% of the aldehyde to per-acid, and passing the preheated mixture at about 60 ft. per second through a reaction zone at a temperature of 350 to 450° F., the time of contact being about 0.2 second and the pressure being substantially equal to atmospheric pressure, mixing benzene vapor with the gaseous mixture removed from the reaction zone for recovery of the per-acetic acid, forming an azeotropic mixture with the acetic acid formed as a by-product, and removing said azeotropic mixture together with unreacted aldehyde and uncondensable gases, from the per-acid, by fractionation.

5. Process for the production of aliphatic per-acids from the corresponding aliphatic aldehyde,

which comprises oxidizing said aldehyde by pre-heating the vapor of said aldehyde to about 200° F. in admixture with an amount of oxygen theoretically insufficient to oxidize more than about 30% of said aldehyde to the per-acid, and passing the preheated mixture at a linear velocity of at least 30 feet per second through a reaction zone at a temperature of 350 to 450° F., the time of contact being from 0.1 to about 1 second and the pressure being substantially equal to atmospheric pressure, the greater part of the gaseous mixture emerging from the reaction zone being recycled to said zone and the remainder being treated for recovery of the per-acid.

6. Process for the production of aliphatic per-acids from the corresponding aliphatic aldehyde, which comprises oxidizing said aldehyde by pre-heating the vapor of said aldehyde to about 200°

F. in admixture with an amount of oxygen theoretically insufficient to oxidize more than about 30% of said aldehyde to the per-acid, passing the preheated mixture at a linear velocity of at least 30 feet per second through a reaction zone at a temperature of 350 to 540° F., the time of contact being from 0.1 to about 1 second and the pressure being substantially equal to atmospheric pressure, mixing benzene vapor with the 10 gaseous mixture removed from the reaction zone for the recovery of the per-acid, forming an azeotropic mixture with the aliphatic acid formed as a by-product, and removing said azeotropic mixture, together with unreacted aldehyde 15 and uncondensable gases from the per-acid, by fractionation.

CERTIFICATE OF CORRECTION.

Patent No. 2,514,585.

March 23, 1943.

JOSEPH E. BLUDWORTH.

It is hereby certified that error appears in the printed specification of the above numbered patent requiring correction as follows: Page 3, second column, line 6, for " 540° F." read -450° F.--; and that the said Letters Patent should be read with this correction therein that the same may conform to the record of the case in the Patent Office.

Signed and sealed this 4th day of May, A. D. 1943.

(Seal)

Henry Van Arsdale,
Acting Commissioner of Patents.
